UNITED STATES PATENT OFFICE

JOHN P. FABER, OF DUNELLEN, NEW JERSEY, ASSIGNOR TO RANSOME CONCRETE MACHINERY COMPANY, OF PLAINFIELD, NEW JERSEY, A CORPORATION OF NEW JERSEY

CHARGING DEVICE FOR CONCRETE MIXERS

Application filed September 13, 1928. Serial No. 305,629.

The present improvements relate primarily to charging devices to concrete mixers, but are not limited to such application, and may be used for charging any mixer or other device in which solids are to be elevated and discharged, and liquids supplied thereto to be mingled therewith.

In devices adapted for preparing freshly mixed concrete for placement, it has become of increasing importance that a definite proportion of water and dry aggregates, etc. be maintained for each given batch. Furthermore, the setting of the freshly mixed concrete is accelerated by the addition of a predetermined amount of calcium chloride solution which should be in proportion to the measured volume of water for each batch.

Inspection requirements as well as State specifications frequently and almost universally call for the addition of an accelerator of the type aforementioned. As the proportions for each batch to be mixed, may vary, it is essential that a measuring means for the water and calcium chloride be provided, which not only will accurately measure the volumes to be discharged into the mixer but also will be rugged and durable, simple to operate and have a minimum of parts.

The primary object among others, is to provide a more efficient, dependable and certain means for measuring the quantity of liquid, discharging it at the proper time and in the proper manner and refilling the liquid receptacle, and one in which the operation of elevating and charging solids, in the present case concrete aggregates, and lowering the loader for another charge automatically discharges, refills and measures the charge of liquid.

A further object is to provide a simple, accurate and automatic primary as well as auxiliary liquid supply means for a mixer, operable under the influence of the loading skip movements.

A further object is to provide a simple, accurate and automatic means whereby a measured quantity of calcium chloride solution may be added to a concrete mixture, operable under the influence of the mixing mechanism.

Other objects and advantages of the pres-

ent improvements will be apparent to those skilled in the art, upon reference to the accompanying drawings in which

The figure illustrates a mixing apparatus embodying one form of the present improvement.

The mixing drum or mixer 1 is of the rotary non-tiltable type, but the present improvements may be used in connection with tilting drums or drums of other description. The mixer 1, having the charging end 2 and discharging end 3 is suitably mounted on frame 4 which in turn is disposed on a suitable frame 5, which latter may have traction means (not shown) as well as power means (not shown) for operating the elements of the apparatus as is well known.

Mounted in slightly elevated position on the frame 5, is a mixing receptacle 6, having agitator or mixing blades 7, which may be manually actuated by handle 8, or automatically operable by rod 9, gears 10, 11 and shaft 12 which latter is operatively connected, with or without a clutch as desired, to the mixer 1, or power means therefor. A storage tank 13 is preferably, although not necessarily, disposed on frame 5, at a lower level than receptacle 6, whereby liquid from the latter may pass under its own head into tank 13 through pipe 14 having a control valve 15.

Disposed intermediate the mixer 1 and tank 13, is a reservoir 16 defining a pump cylinder, which communicates with said tank through pipe section 17, and with the charging mouth 2 of the mixer by pipe 18. As illustrated, these pipes are equipped with suitably disposed check valves 19 and 20 respectively. A plunger 21, mounted in reservoir 16, is adapted to reciprocate therein and is disposed in air tight relation to the inner wall thereof, whereby the arrangement functions as a single action pump as hereinafter described. In the present illustration the left hand face of reservoir 16 is axially perforated at 22 to accommodate actuating rod 23, one end of which is fixed to plunger 21 and the other end pivotally connected to link 24, said link in turn being pivotally connected to actuating lever 25.

The lever 25 is vertically disposed for transmitting horizontal sliding movement to the plunger 21. The lower end of said lever is pivotally connected at 26 to an adjustable block 27 while the upper end 25' thereof is free and located in the path of travel of dog 28 suitably mounted on loading skip 38. The block 27 is axially bored and internally threaded for travel on screw rod 29, which is mounted in bearings 30 and 31 for rotary but not longitudinal movement. Upon turning knobs 32 or 33 it is obvious that the block 27 may be caused to travel to the right or left as desired, carrying with it the lever fulcrum 26. A tension spring 34 is secured at one end to any fixed point, for example, frame 5, while its other end is secured to lever 25 at 35 as illustrated. Although the foregoing lever arrangement and adjusting means therefor is preferably used and is reliable it is obvious that other modified forms will occur to those familiar with the art.

Referring now to the primary water supply means, the present improvements preferably include a measuring tank of the type described and claimed in the copending application of George T. Allen, filed Aug. 27, 1926, Serial No. 131,822. Reference may be had to that application for details of construction. Broadly described this arrangement includes a water measuring tank 39 mounted on the loading skip 38, pivotally mounted at 37, having a water supply pipe 40 with a valve 41 controlling the inlet therefrom to the tank 39. Said valve 41 is equipped with an adjustable float 42 on the stem thereof whereby as the water rises in tank 39, the float will function to close off the supply. This float 42 may be adjustably positioned along the valve stem so that only a predetermined measured amount of water may enter tank 39. As the skip 38 is elevated by power cable 43, the measured amount of water in the tank is automatically discharged through spout 44 into the mixer 1 along with the dry aggregates from the skip. Upon downward movement of the skip 38, the valve 41 is automatically and positively opened by trip 45 as fully set forth in the aforesaid copending application.

Preparatory to operation, the mixing receptacle 6 is charged with water and calcium chloride in fixed proportions and thoroughly stirred and agitated until dissolution is accomplished and the required calcium chloride solution is obtained. This solution may then be transferred to the storage tank 13 by opening valve 15, and while the charging operation of the mixer is taking place, an additional calcium chloride solution may be prepared in receptacle 6 without interfering with the normal functioning of the mixer. At this time, the plunger 21 is in the position illustrated, i. e., the left hand portion of reservoir 16, and the calcium chloride solution from

tank 13 may enter said reservoir under its own head, through check valve 19, until the reservoir 16 in advance of the plunger 21 is full and some solution may even enter pipe 18 until the level therein is the same as that in tank 13. The system for supplying the auxiliary liquid to the mixer is now ready for its adjustments, although the latter may be made prior to the charging of the tank and reservoir, if desired. The adjustable block 27 may now be set by actuating screw 29 and a suitable scale may be provided if desired. Movement of the block 27 will alter the position of the fulcrum 26 thereby correspondingly altering the position of the free end of lever 25'. It is notable however, that the piston or plunger 21 does not partake of this movement but remains at the left hand limit of its travel under the urge of spring 34. By locating block 27 to the left of its illustrated position the stroke of the plunger is shortened, while locating it to the right of its illustrated position will lengthen the plunger stroke. These adjustments obviously change the angle at which the operating lever 25 stands.

The primary liquid supply means, viz. tank 39, is set to admit thereto the measured amount of water which is to go into the mixer 1 along with the dry aggregates in the skip 38. The movable pivot 26 is set accordingly, as the amount of calcium chloride solution to be added is in a fixed proportion to the measured amount of water in tank 39. This ratio is usually three gallons of the solution to one cubic yard of concrete. The amount of water measured in tank 39 is in a fixed proportion to the dry aggregates. In view of this, it is apparent that the liquids must be carefully and accurately measured, both with respect to each other as well as to the dry ingredient.

Upon operation, the skip 38 is raised by cable 43 until the dry aggregates in the skip 38 and the water in tank 39 discharge by gravity into the mixer 1. During this movement, the dog 28 on skip 38 describes an arcuate course and contacts the free end of lever 25 forcing it to the right about fulcrum 26, and at substantially the same time thrusting plunger 21 to the right in opposition to spring 34, thereby positively forcing a quantity of the calcium chloride solution in reservoir 16 out through pipe 18 into the mixer 1. At this time check valve 19 closes and prevents return of the solution to tank 13, and check valve 20 opens to permit the solution to pass. It is seen therefore that the distance the piston travels determines the volume of the solution forced into the mixer. By reason of the adjustable pivot 26, the point in the travel of the loading skip 38 at which it strikes lever 25 can be varied and therefore the amount of travel which the skip imparts to said lever is also varied and in this manner

the length of stroke of the plunger is varied. This arrangement therefore automatically measures the quantity of solution forced into the mixer at each advance stroke of the plunger, one stroke being made each time the loading skip is raised.

Upon return of the skip 38 to lower position for receiving another charge of aggregates, the tank 39 is again automatically charged, by reason of the positive opening of valve 41 as described in the aforementioned Allen application. This lowering movement of skip 38, withdraws dog 28 and concurrently spring 34 functions to return lever 25 and plunger 21 to normal position.

During this movement, the plunger 21 is traveling to the left in reservoir 16, which establishes a suction therein and positively withdraws a new supply of solution from tank 13 through valve 19 into the reservoir to be ready for the subsequent discharge therefrom.

It is therefore notable that the volume of the primary water supply may be measured, and the volume of the auxiliary calcium chloride supply may be measured according to specifications. Furthermore, the adjustments may be set according to the specifications and need not thereafter be attended to, since the entire charging and discharging operations throughout are automatic and operable, without the attention of any operator, under the influence of the movements of the skip 38.

Although the embodiment chosen for illustration for carrying out the present improvements is preferable, it is apparent that other means may be employed. The adjustment of pivot 26 may be accomplished by mechanism other than that illustrated. Furthermore, the measuring of the calcium chloride solution may be accomplished by employing the tank 39 mounted on the skip 38 according to the aforementioned Allen application and the primary water supply means may comprise a measuring tank of known construction located on the frame 4 or 5. The present improvements further contemplate the location of both the water supply means and the calcium chloride solution supply means on the skip for movement therewith. Such an arrangement may be accomplished by having two tanks 39 on the skips, with the necessary structural details for measuring, included, or a single tank on the skip with a dividing partition therein, forming a water compartment and a calcium chloride compartment.

The present improvements have many advantages which will be apparent to those familiar with the construction and operation of devices of this character. An advantage not apparent resides in the fact that an engineer or inspector may fix the float 42 so as to limit the quantity of water used in each batch of concrete, and may fix the adjustable

block 27 so as to limit the quantity of calcium chloride used in each batch of concrete, and may apply thereto for use in connection therewith a locking device which will insure against the use of an inappropriate quantity of water or calcium chloride. The operator also having fixed the position of the float, as well as the position of the adjustable block, and consequently the quantity of water and calcium chloride solution used with each batch, need give the apparatus no further attention and can be assured that the proportionate quantities will be maintained and discharged automatically into the mixer with each load of solid aggregates.

I claim:

1. The combination with a mixer and a pivotally mounted skip movable from a receiving position to a discharging position where it discharges into the mixer, of a liquid measuring mechanism including flow inducing means for charging and discharging same, adjustable means for controlling said means, all so constructed and arranged to operate under the influence of said skip.

2. In a mixing device, the combination with a mixer, of a movable loading device movable from a receiving position to a discharging position where it discharges into the mixer, liquid supply means for said mixer including a mixing receptacle and a storage tank, common means for withdrawing a predetermined quantity of liquid from said tank and for forcing it to said mixer, said last mentioned means being responsive to raising and lowering movements of said loading device.

3. In a mixing device, the combination with a mixer, of a pivotally mounted skip movable from a receiving position to a discharging position where it discharges into the mixer, liquid supply means for said mixer including a mixing receptacle and a storage tank, adjustable means intermediate said skip and tank for positively incepting the flow of a predetermined quantity of liquid from said tank and positively discharging a measured quantity thereof to said mixer, said last mentioned means being responsive to pivotal movements of said skip.

4. In a device of the character described the combination of a mixer, a movable loading device adapted to receive and discharge dry aggregates into said mixer, a primary liquid supply means adapted to discharge into said mixer, a secondary liquid supply means adapted to discharge into said mixer, both of said means being responsive to movements of said loading device and one of said means comprising positive replenishing and discharging mechanism therefor.

5. In a device of the character described, the combination of a mixer, a movable loading device adapted to receive and discharge dry aggregates into said mixer, a liquid supply means for said mixer including a storage

tank and a communicating reservoir, a plunger in said reservoir and means for actuating said plunger, operated by said loading device.

6. In a device of the character described, the combination of a mixer, a movable loading device adapted to receive and discharge dry aggregates into said mixer, a liquid supply means for said mixer including a storage tank and a communicating reservoir, a plunger in said reservoir, means for actuating said plunger operated by said loading device and adjustable means for varying the stroke of the plunger.

7. In combination with a mixer and loading device therefor, a calcium chloride attachment operable under the influence of one of the aforementioned elements and comprising a tank for calcium chloride solution, a pump for withdrawing solution from said tank and conveying same to the mixer and adjustable means for predetermining the volume discharged by said pump.

8. Apparatus for supplying calcium chloride solution to concrete mixers and the like comprising a mixing receptacle, a storage tank communicating therewith, a reservoir communicating with said tank and having an outlet adapted to discharge into a mixing drum, a plunger disposed in said reservoir, actuating means for said plunger, means for adjusting the travel of said plunger, said actuating means being positioned and constructed for movement in response to movements of the loading skip of a concrete mixer.

9. In a device of the character described the combination of a mixer, a movable loading device adapted to receive and discharge dry aggregates into said mixer, a primary liquid supply means movable with said loading device and adapted to discharge into said mixer, a secondary liquid supply means adapted to discharge into said mixer each of said means including a liquid measuring mechanism and each of said means being automatically operable in response to movements of said loading device.

10. In a device of the character described the combination of a mixer, a pivotally mounted skip adapted to receive and discharge dry aggregates into said mixer, a primary liquid supply means for said mixer mounted on said skip and adapted to be charged and discharged under the influence of the skip movements, a secondary liquid supply means adapted to discharge into said mixer, each of said means including a liquid measuring mechanism and said secondary means being operable in synchronism with said skip.

11. In a device of the character described, the combination of a mixer, a movable loading device adapted to receive and discharge dry aggregates into said mixer, a liquid supply means for said mixer including a storage

tank, a reservoir, a valve controlled conduit communicating between said tank and reservoir, a valve controlled conduit communicating between said reservoir and mixer, common mechanical members for alternately withdrawing liquid from said tank to said reservoir and for expelling said liquid from said reservoir to said mixer and actuating means for said members responsive to movements of said loading device.

12. The combination with a mixer, and a movable loading device therefor, of pump means for conveying liquid from a source of supply to said mixer operable in response to raising and lowering movements of said device whereby movement in one direction accomplishes a suction stroke and in another direction creates a force stroke.

Witness my hand this 11th day of September, 1928, County of Middlesex, State of New Jersey.

JOHN P. FABER.
